UNITED STATES PATENT OFFICE.

OTTO LIEBKNECHT, OF FRANKFORT-ON-THE-MAIN, GERMANY, ASSIGNEE TO THE ROESSLER & HASSLACHER CHEMICAL COMPANY, OF NEW YORK, N. Y., A CORPORATION OF NEW YORK.

PROCESS OF MAKING ALKALI PERBORATES.

1,253,060.

Specification of Letters Patent.

Patented Jan. 8, 1918.

No Drawing.

Application filed May 31, 1916. Serial No. 100,921.

To all whom it may concern:

Be it known that I, OTTO LIEBKNECHT, a subject of the German Emperor, and resident of Frankfort-on-the-Main, Germany, have invented certain new and useful Improvements in Processes of Making Alkali Perborates, of which the following is a specification.

This process relates to the art of making 10 perborate and it particularly relates to a process for the electrolytic production of alkali perborate by an electrolytic process.

In U. S. patent application, Serial No. 70,591 filed Jan. 6, 1916, I have described 15 the manufacture of alkali perborate consisting in a double decomposition of a solution of electrolytically produced alkali percarbonate with a solution of an alkali borate and particularly a process of making sodium 20 perborate consisting in electrolyzing a solution of an alkali carbonate and a sodium borate.

According to my application mentioned above, sodium perborate is produced easily, 25 if the work is carried out in the presence of solid perborate of sodium.

I found, however, that there is yet another method affording even greater convenience in manufacturing the alkali-perborate by continuously maintaining the electrolyte completely saturated with borax and soda; in order to achieve this end, borax and soda must be present in the solid phase.

As to whether, and if so in which way, the 35 current density affects the yield of perborate in the electrolytic process, I have found that contrary to the experience hitherto gained in the electrolysis of salt solutions to oxidize said salts, the yield increases within wide 40 limits by increasing the current density, the yield depending upon a high density of current at the cathode as well as at the anode.

In the electrolytic oxidation of salts it has been the universal practice to work at the anode with a current density which was low 45 as compared with that prevailing at the cathode. As I have found that I can improve the yield of perborate by applying a high current density at the anode, I can of course reduce the surface of the anode so 50 that my new process works in the direction of making the current density at the anode approximately equal to that of the cathode.

I claim:

1. The process of making alkali perborate, 55 consisting in electrolyzing a substantially saturated solution of an alkalicarbonate and alkali borate with a current density approximately equally high at both the cathode and anode.

2. The process of making alkali perborate, 60 consisting in electrolyzing a substantially saturated solution of an alkalicarbonate and alkali borate with a current density approximately equally high at both the cathode and anode, and replenishing both alkali salts in 65 solid form to continuously maintain the solution saturated with them.

3. The process of making sodium perborate, 70 consisting in electrolyzing a substantially saturated solution of a sodium carbonate and sodium borate with a current density approximately equally high at both the cathode and anode.

In testimony whereof I have signed my 75 name to this specification in the presence of two subscribing witnesses:

OTTO LIEBKNECHT.

Witnesses.

JEAN GRUND,
HARRY EDWIN CARLSON.
